Des. 224,749
Patented Sept. 12, 1972

224,749

CLOCK RADIO

Samuel Cohen, 666 Wildwood Road,
West Hempstead, N.Y. 11552

Filed June 8, 1971, Ser. No. 151,159

Term of patent 14 years

Int. Cl. D10—01

U.S. Cl. D42—7

FIG. 1.

FIG. 2.

FIG. 1 is a perspective view of a clock radio in a closed position showing my new design;

FIG. 2 is a perspective view of the clock radio of FIG. 1 in an open position.

The rear and bottom of the clock radio are unornamented except for continuation of the simulated strap thereabout.

I claim:

The ornamental design for clock radio, substantially as shown and described.
